Patented Aug. 19, 1975

236,387

HOLDER FOR OSTOMY DRAINAGE BAG

Marvin Katzman, 1520 202nd St., Bayside, N.Y. 11360,
and Neil De Fluri, 952 Arnet Ave., Union, N.J. 07083

Filed Jan. 28, 1974, Ser. No. 437,134

Term of patent 14 years

Int. Cl. D2—02; D24—03

U.S. Cl. D83—1 P

FIG. 1

FIG. 2

FIG. 3

FIG. 4

FIG. 5

FIG. 1 is a front view of a holder for ostomy drainage bag, incorporating our new design.

FIG. 2 is a rear view thereof.

FIG. 3 is a top plan view thereof.

FIG. 4 is a bottom plan view thereof.

FIG. 5 is a top perspective view thereof.

We claim:

The ornamental design for a holder for ostomy drainage bag, as shown and described.
